UNITED STATES PATENT OFFICE.

ALEXANDER RUSSELL, OF NOBLESTOWN, PENNSYLVANIA.

RAIL-JOINT.

SPECIFICATION forming part of Letters Patent No. 722,538, dated March 10, 1903

Application filed August 15, 1902. Serial No. 119,802. (No model.)

To all whom it may concern:

Be it known that I, ALEXANDER RUSSELL, a citizen of the United States of America, residing at Noblestown, in the county of Allegheny and State of Pennsylvania, have invented certain new and useful Improvements in Rail-Joints, of which the following is a specification, reference being had therein to the accompanying drawings.

10 This invention relates to certain new and useful improvements in rail-joints, and relates more particularly to that class wherein the use of nuts and bolts is entirely dispensed with.

15 The present invention has for its object the provision of novel means whereby two sections of the rails may be securely clamped and retained together in proper position upon the cross-ties; furthermore, to provide novel 20 means that will permit the rails to be readily removed when desired.

25 My present invention further aims to provide a novel form of locking means that will prevent the locking or wedge-shaped fish-plate from becoming loose.

30 A still further object of my invention is to provide a device of the character described which will be extremely simple in construction, strong, durable, comparatively inexpensive to manufacture, and highly efficient in 35 its use.

With the above and other objects in view the invention consists in the novel construction, combination, and arrangement of parts 35 to be hereinafter more fully described, and specifically pointed out in the claims.

40 In describing the invention in detail reference is had to the accompanying drawings, forming a part of this specification, and 45 wherein like numerals of reference indicate like parts throughout the several views, in which—

Figure 1 is a perspective view showing my improved rail-joint applied to the meeting 45 ends of the rails. Fig. 2 is an end view thereof. Fig. 3 is a perspective view of the locking fish-plate. Fig. 4 is a similar view of the plate or strip of metal that may be used in case there is an irregularity formed in the 50 web of the rail.

In the drawings the reference-numeral 1 represents the cross-tie, upon which is secured,

by means of spikes 2, the plate 3, the latter having formed integral therewith a chair 4.

In said chair are secured the rails 5, which 55 are held in position and are wedged therein by means of the locking fish-plate 6, said locking fish-plate having a bevel side 7, which engages the beveled inner face 8 of the chair, thereby preventing the upward displacement 60 of the same. This locking fish-plate 6 is slightly beveled and is drawn in endwise adjacent to the webs of the rails and the bevel side 8 of the chair. In the contracted end of the wedge-shaped plate are formed a series of 65 apertures 9, which extend therethrough and are adapted to receive the cotter-pin 10, which forms a key or lock preventing the lineal displacement of the locking fish-plate. This cotter-pin has its ends turned outwardly and 70 abuts against the wall of the chair. In the locking fish-plate is also formed a recess 11, and a corresponding recess 12 is formed in the integral portion of the chair extending against the web, flange, and tread of the rail. 75

Filler plates or strips are indicated by numeral 14 and are only employed in cases where there is an irregularity in the formation of the web of the rail. These plates or strips are arranged against the web of the 80 rail in order to obtain a uniform thickness of the web when the same is wedged between the locking fish-plate and integral portion of the chair. I find that by extending the integral portion of the chair which extends on 85 the outer face of the rail to a distance almost flush with the upper face of the tread of the rail the same will be more substantially braced and the spreading of the rails will be 90 impossible.

In order to remove the rails, the cotter-pin is first removed and the locking fish-plate is driven in the opposite direction, when it may be easily removed, thus permitting ready access to the rails. 95

It will be noted that the rails will be permitted to expand and contract, and the chair is also fastened in a manner to the cross-ties that will permit of expansion and contraction caused by the difference in temperature. 100

It will be particularly noted that various changes may be made in the details of construction without departing from the general spirit of my invention.

Having fully described my invention, what I claim as new, and desire to secure by Letters Patent, is—

1. In a rail-joint, the combination with the rails, of a chair to receive said rails, a wedge-shaped locking-plate of greater length than the said chair, said locking-plate being formed adjacent one of its ends and intermediate its sides with a series of openings, and a locking means arranged in one of the said openings.
2. The combination with the rails, of a chair, said chair having one of its inner faces inclined inwardly from the base of the chair, a wedge-shaped locking-plate formed intermediate its sides with a series of openings, said locking-plate having its outer edge inclined outwardly from its upper face, and engaging the inclined face of the said chair, and a locking means adapted to be received in any of the said openings, substantially as described.
3. In a rail-joint, the combination of the rails, a chair, a wedge-shaped fish-plate having a series of openings formed therein, fastening means extending through one of said

openings, and filler-plates secured adjacent 25 to said rails, substantially as described.

4. The combination of the rails, a chair, to receive the said rails, a locking-plate of greater length than the said chair, said locking-plate being formed with a series of openings, and a locking means arranged in one of the said openings and engaging one of the ends of the said chair, substantially as described.

5. The combination with the rails, of a 35 chair to receive said rails, a locking-plate arranged in the said chair, said locking-plate having its inner face recessed, and a filler-plate arranged in the recess of the said locking-plate, substantially as and for the purpose specified.

In testimony whereof I affix my signature in the presence of two witnesses.

ALEXANDER RUSSELL.
